UNITED STATES PATENT OFFICE.

CHARLES F. GAUEN, OF ST. LOUIS, MISSOURI.

HAT-FASTENER.

SPECIFICATION forming part of Letters Patent No. 678,725, dated July 16, 1901.

Application filed September 5, 1900. Serial No. 29,064. (No model.)

To all whom it may concern:

Be it known that I, CHARLES F. GAUEN, a citizen of the United States, residing in the city of St. Louis, in the State of Missouri, have 5 invented certain new and useful Improvements in Ladies' Hat-Holders, of which the following is a full, clear, and exact description, reference being had to the accompanying drawings, forming part of this specification.

My invention relates to a device for retaining ladies' hats upon their heads, the device being of such a nature as to be readily applied to the article of headwear and easily 15 placed into position in putting the hat upon the head.

The invention consists in features of novelty hereinafter fully described, and pointed out in the claims.

20 Figure I is a perspective view of the holder. Fig. II is an enlarged detail view of the slide-wires, the slides thereon, (one in section,) and the inner ends of the spring-arms. Fig. III is a view illustrating the under side of the 25 crown of a hat, showing the holder arranged therein. Fig. IV is a sectional view through a hat equipped with the holder illustrated in position assumed on the head.

1 and 3 designate wires that are joined by 30 loops 2, located at the ends of the wire 1.

These wires are bent into uniform curvature, and the wire 3 is provided with prongs 4 at its ends. Secured to the wires midway of their length is a staple 5, the said staple, 35 in connection with the looped ends of the wire 1, serving to hold the wires a uniform distance apart throughout the length of the wire 1.

6 designates apertured slides mounted on 40 the wires 1 and 3 and adapted to be moved thereon between the centrally-located staple 5 and the loops 2.

7 designates spring-arms bent at 8 and pivotally connected to the slide 6 at 9.

45 In the practical use of this device the holder is secured to the hat by placing it within the base of the crown thereof, embedding the prongs 4 and staple 5 into the hat. The spring-arms 7 are then grasped by the wearer 50 of the hat and spread apart a sufficient distance to permit of their straddling the head. The hat is then placed upon the head and the spring-arms are carried rearwardly at the same time into the position seen in Fig.

IV, where they embrace the head from opposite sides and retain the hat from escape. By 55 changing the position of the slides 6 on the wires 1 and 3 the degree of spread of the spring-arms 7 may be increased or lessened, so as to make the device adaptable for large 60 or small heads or to cause the spring-arms to embrace the head more or less tightly. When the slides are moved inwardly toward the position of the staple 5, the spread of the spring-arms is increased, whereas when they are 65 moved in the opposite direction the spread is lessened. By hinging the arms to the slides the arms may be caused to embrace the head at any desired angle with relation to the part of the holder by which they are carried or the 70 hat. On the removal of the hat the spring-arms may be moved on their hinges into the interior of the hat for convenience.

I claim as my invention—

1. The combination of a holder-frame attached to an article of headwear, a pair of independent spring-arms individually hinged to said frame so that they may be raised or lowered according to the position it is desired to cause them to embrace the head. 75

2. The combination of a holder-frame attached to an article of headwear, a pair of independent spring-arms and individual hinged connections between the frame and arms whereby the arms may be raised or lowered 85 according to the position it is desired to cause them to embrace the head.

3. In a hat-holder, the combination of a pair of wires adapted to be secured within the article of headwear, slides arranged on 90 said wires, and spring-arms hinged to said slides and adapted to embrace the head on opposite sides, substantially as described.

4. In a hat-holder, the combination of a pair of wires connected together and provided 95 with prongs, a pair of slides arranged on said wires, and spring independent arms individually hinged to said slides, substantially as described.

5. In a hat-holder, the combination of the 100 pair of wires connected together, a pair of slides movably mounted on said wires, and a pair of spring-arms hinged to said slides, substantially as described.

CHARLES F. GAUEN.

In presence of—

E. S. KNIGHT,
M. P. SMITH,
